CLAIM

The ornamental design for a bottle and cap, as shown and described.

DESCRIPTION

FIG. 1 is a perspective view of the bottle and cap.

FIG. 2 is top plan view thereof.

FIG. 3 is a bottom plan view thereof.

FIG. 4 is a front elevational view thereof.

FIG. 5 is a back elevational view thereof.

FIG. 6 is a right side elevational view thereof.

FIG. 7 is a left side elevational view thereof.

FIG. 8 is a perspective view of a second embodiment of the bottle and cap.

FIG. 9 is top plan view thereof.

FIG. 10 is a bottom plan view thereof.

FIG. 11 is a front elevational view thereof.

FIG. 12 is a back elevational view thereof.

FIG. 13 is a right side elevational view thereof.

FIG. 14 is a left side elevational view thereof.

FIG. 15 is a perspective view of a third embodiment of the bottle and cap.

FIG. 16 is top plan view thereof.

FIG. 17 is a bottom plan view thereof.

FIG. 18 is a front elevational view thereof.

FIG. 19 is a back elevational view thereof.

FIG. 20 is a right side elevational view thereof; and,

FIG. 21 is a left side elevational view thereof.

The broken lines in the views depict environmental structure that is shown for illustrative purposes only and that does not form any part of the claimed design.

1 Claim, 12 Drawing Sheets

Related U.S. Application Data

continuation-in-part of application No. 29/407,664, filed on Nov. 30, 2011, now Pat. No. Des. 720,622.
